ABSTRACT: An earth scraper is provided with a bucket adjustable mounted between two tractor units for loading and unloading operations in either direction. The bucket is provided with a movable transverse partition supported and guided by a pair of outwardly turned channel shaped flanges on either side of the bucket and the drive mechanism for moving the partition is protectively disposed within the channel shaped flanges.

LOADING AND UNLOADING EQUIPMENT FOR MOTOR SCRAPER

In a conventional arrangement, a single-ended motor scraper comprises a conveyor bucket or loader towed by a two-wheeled tractor coupled thereto at the front end. The loader rests at the rear on an axle having free wheels or driven wheels which cannot be steered. To discharge collected material, the interior of the bucket is provided with a displaceable transverse partition which is moved forward by a mechanism for unloading the bucket. The mechanism can then move the partition rearwardly into contact with the rear transverse wall of the scraper where it will remain during loading operations. The movements of the partition are controlled by a centrally located hydraulic jack or rack and pinion mechanism which passes through the rear wall and extends beyond it. Thus, motor scrapers of known types most frequently comprise a center jack prominently projecting above or below the rear axle of the loader which is an impediment in certain circumstances.

The object of the present invention is to avoid this disadvantage which prevents the loading and unloading of a reversible motor scraper using two tractors, each having two wheels, at the front and rear of the bucket. Such a motor scraper comprises a center bucket coupled to a pair of two-wheeled tractors, one at the front and the other at the rear. It is known that this arrangement makes it possible to obtain a motor scraper of great power capable of moving in either direction, and capable of effecting maneuvers, which cannot usually be performed with conventional motor scrapers. It is obvious that the projection and usual position of the center jack which actuates the partition of a conventional loader, would not permit the normal functioning of a reversible motor scraper which comprises, at each end of the loader, a scraping blade and an articulated loading door, which door remains closed during transport and is raised when loading or unloading.

A loading and unloading mechanism according to the present invention comprises a displaceable transverse partition within the bucket or loader, and is characterized in that the upper edges of the two longitudinal walls of the bucket are each provided with a longitudinal rolling or sliding channel for a truck, the two trucks being transversely connected by the displaceable partition and each being capable of displacement by means located within the rolling or sliding channel.

According to a preferred embodiment of the present invention the straight upper edges of the sidewalls of the bucket are turned outwardly so that each forms a longitudinal channel serving simultaneously to stiffen or reinforce the walls of the bucket and as a protecting hood for the displacement mechanism of the partition. This mechanism may be one or more hydraulic or pneumatic jacks, a screw system, a rack and pinion device, or the like.

The accompanying drawings will enable the features of the present invention to be more clearly understood:

FIG. 1 is a plan view of a reversible scraper according to the invention.

FIG. 2 is a cross section of the line II—II of FIG. 1.

FIG. 3 is an elevation of the scraper and the members which connect it to the two-wheeled tractors.

FIG. 4 is a partial longitudinal section of the upper part of the scraper and its partition, showing the displacement mechanism operated by jacks and the rack synchronization mechanism.

FIG. 5 is a partial cross section, corresponding to FIG. 2 showing on a magnified scale the details of one of the upper edges of the bucket.

FIG. 6 is an alternative construction for the synchronization rack.

FIG. 7 is a side view of FIG. 6.

FIG. 8 is an elevation showing schematically a reversible motor scraper assembly in accordance with the invention.

FIG. 9 is a construction alternative to FIG. 4 in which the displacement of the partition is effected by a rack mechanism.

FIG. 10 is a further alternative having a male and female screw action.

FIG. 11 shows a method by which a motor scraper according to the invention can unload its material.

FIG. 12 shows another type of work which may be performed by the scraper.

FIG. 8 shows a reversible motor scraper comprising a pair of two-wheeled tractors 1 and 2 arranged back to back and carrying a center bucket or loader 3 therebetween. The coupling of the bucket by two horizontal articulated shafts 4 and 5 and its control by jacks 6 and 7 are already known. It is also known to provide at each end of the loader 3 a movable door 8, 9 and a scraper blade 10, 11. The bucket 3 is a container, the plan view of which is rectangular (FIG. 1) and the upper edges of the two longitudinal walls 12 and 13 are each provided with a rolling or sliding channel 14, 15 over which trucks 16, 17 move. The two trucks 16 and 17 are connected together by a transverse partition 18 which is movable within the bucket 3.

According to one embodiment, the two trucks 16, 17, and the partition 18 form a single rigid member capable of displacement in either direction, as shown by the arrow 19 in FIG. 1. According to another embodiment, the trucks 16 and 17 are linked to vertical shafts (not shown) placed on each side of the partition 18 and in this case, the partition 18 and the two trucks 16 and 17 are displaced like an articulated girder.

The length 20 of each of the trucks 16 and 17 is sufficient to ensure a strong vertical seat for the displaceable partition 18, the longitudinal displacement of which effects emptying of the center bucket 3. The trucks 16 and 17 are symmetrical, both relative to the vertical plane defined by transverse partition 18 and relative to the center longitudinal plane 21 of the bucket 3. They are sufficiently raised at their center portion which projects above the side edges 14 and 15 (FIG. 3) to effect a firm connection with the displaceable partition 18 and enable the latter to withstand the pressure of the loaded material. The projection of the partition 18 and the trucks 16 and 17 above the edges 14 and 15 of the bucket 3 also ensures correct and complete emptying of the material which may be heaped up on each side of partition 18.

The rolling and sliding channels 14 and 15 are sufficiently rigid to withstand the bending action imposed thereon by the weight of the material to be unloaded and they also act as borders for the displaceable partition 18. It is an advantage to protect the mechanisms within these lateral sliding or rolling channels and thus they may be formed as shown in FIG. 5. In this case the straight upper edge of the sidewall 12 of the bucket is turned outwardly downwardly, inwardly and upwardly so as to form a longitudinal channel serving both as a reinforcement for the walls of the bucket 3 and as a hood to protect the displacement mechanism. The rolling or sliding members are accommodated within this channel. In the case of FIG. 5, sliding means 22 are shown. The displacement members for the truck 16 are formed by two multiple telescopic jacks 23 and 24 which are disposed within the channel 14. When the partition is pushed to one end by one of the jacks, the opposing jack is telescoped within itself to permit the partition to reach the end of its travel. However, the bodies of the jacks may also project from the opposite ends of the bucket. The same method of assembly applies to the truck 17 and its sliding or rolling channel 15.

It will be apparent that the outer casing 25 of the trucks 16 and 17 is bent inwardly at its lower portion (FIG. 5) under the turned-over edge of the rolling or sliding channel 14 or 15, thus ensuring good protection of the displaceable members.

The telescopic jacks are arranged in two pairs 23 and 24. Each pair works in opposition. To ensure perfectly uniform displacement of the partition 18 (to prevent a slanted position which would be prejudicial particularly in the case of a rigid connection between 16, 17, 18), each truck 16 and 17 has a pinion such as 26 (FIGS. 4 and 5) which meshes with a fixed longitudinal rack 27. Each of the racks 27 is disposed under the upper edge of the rolling or sliding channel 14 or 15 with which it corresponds. Synchronization of the two pinions 26 is ensured by a transverse shaft 42 which rotates loosely in the

upper part of the displaceable partition 18 and on each end of shaft 42 a pinion 43 is keyed. Trains of pinions 44, 45 and 46 provide a geared connection between each pinion 43 and the corresponding pinion 26 which in turn meshes with rack 27.

In FIGS. 6 and 7 the rack 47, which is equivalent to rack 27 in FIG. 5, is mounted on the upper surface of the channel along the top edge of the sidewall and is disposed in direct meshing engagement with pinion 43.

FIG. 9 shows an alternative embodiment of the displacement mechanism of the transverse partition 18. In this case each channel 14, 15 comprises an inverted rack 28 with which a pinion 29 meshes. This pinion 29 is located within the corresponding truck 16 or 17. The two pinions 29 are keyed on the same transverse shaft and rotated by a reduction drive (not shown) supported by the displaceable partition 18.

In FIG. 10, the movements of the partition 18 are controlled by a male screw 30 and a female screw 31. A screw 30 is disposed in each channel 14, 15, while a female screw 31 is disposed in each truck 16 or 17. Two embodiments are possible in which the screws 30 are rotated in female screws 31 fixed to the trucks, or the screws 30 are stationary while the female screws 31 are rotated by a reduction drive or by two electrically synchronized reduction drives.

The construction shown in FIGS. 9 and 10 assume that the scraper has an electric current generator, which is the case for many high powered motor scrapers.

The operation is as follows:

It is known that the increasing resistance to the intake of materials in the loader 3 which results from the advancing movement of the tractor, and makes it necessary to interrupt scraping, is due to the limitation of the volume of the buckets 3 of motor scrapers. With a reversible motor scraper fitted with a displaceable partition 18 this disadvantage is eliminated. After placing the partition 18 in a median position that is to say, in the center of the loader 3, the apparatus can be used by filling the two compartments 32 and 33, thus defined, in succession. When the motor scraper moves in the direction of the arrow 37, the scraped materials fill the compartment 32. When the motor scraper returns for the following pass in the direction of the arrow 40, the materials fill the compartment 33 of the bucket 3. Consequently it will be seen that the arrangement according to the invention makes it possible to double the filling capacity, even without increasing the power consumed. Moreover the increase in the load increases the gripping power of the driving wheels.

During the unloading of the apparatus (FIG. 11) moving in the direction of the arrow 36, the compartment 33 at the rear of the partition 18 is unloaded first. The other compartment 32 is unloaded on the return, i.e., the machine unloads to the rear relative to the direction of travel. Consequently, the loaded materials always flow out of the bucket 3 to the rear, relative to the direction of travel, while in the conventional arrangement using only one tractor, they are emptied by being

pushed out the forward end and then flow backwardly under the bucket, a feature which is a disadvantage and requires more power for emptying.

FIG. 12 shows a type of work for which the apparatus of the present invention is well suited. It is assumed that at the start the partition 18 is disposed at the front of the bucket 3, while the scraper is travelling in the direction of the arrow 37. The rear compartment 33 is initially full of material 38 which it has either loaded itself by scraping or received by decanting. The forward compartment 32 is initially empty and of small capacity. The bucket 3 is inclined so as to scrape the ground by means of the front blade 11 and at the same rate as the earth 39 fills the compartment 32 the partition 18 is pushed back in the direction of the arrow 40 to empty a layer 41 of material 38 onto the ground. Thus, by a single passage of the scraper, the ground is scraped, the forward compartment 32 is loaded, the capacity of which increases at the same rate as the partition 18 recedes, and due to the displacement of the partition 18, a layer 41 of material 38 which has previously been loaded, is deposited in its place. This makes it possible to construct in a single passage a temporary macadamized road after simple removal of the layer of superficial earth.

What is claimed is:

1. A loading and unloading reversible scraper for use in earth moving and similar operations comprising, a bucket having a bottom, two longitudinal sidewalls and transverse end walls, each of said end walls being movable relative to said bottom, a transverse partition displaceable within said bucket, a two-wheeled tractor connected at each end of said bucket, the upper edges of said two longitudinal sidewalls of said bucket each being provided with a longitudinal flange means defining a pair of channels, a pair of trucks supported by said flange means and connected to opposite ends of said displaceable partition, and means within said channels for longitudinally displacing said truck along said flange means.
2. A scraper as set forth in claim 1 wherein each of said trucks are provided with downwardly and inwardly turned flanges and means secured to said inwardly turned flanges disposed in cooperating supporting and guiding relations with said channel.
3. A scraper as set forth in claim 1 wherein the displacement means is formed by at least one hydraulic jack.
4. A scraper as set forth in claim 3 wherein a pair of hydraulic jacks are disposed on opposite sides of said partition in each of said channels.
5. A scraper as set forth in claim 1 wherein the displacement means is comprised of drive pinion means mounted on said trucks and rack means mounted on said channels, said rack-and-drive pinion means being enclosed within said channels.
6. A scraper as set forth in claim 1 wherein said displacement means is comprised of male screw means mounted in said channel, female screw means mounted in said truck and means for driving one of said male and female screw means.
